UNITED STATES PATENT OFFICE

2,510,861

MOBILE FIRE EXTINGUISHER

Stewart Beal, Winnetka, Ill., assignor to Randolph Laboratories, Inc., Chicago, Ill., a corporation of Illinois

Application September 13, 1946, Serial No. 696,834

4 Claims. (Cl. 169—31)

1

The present invention relates to fire extinguishers and especially to a novel mobile or portable fire extinguisher assembly of the carbon dioxide type.

Among the objects of the present invention is to provide a novel fire extinguisher assembly that may be readily and easily transported from a place of storage to a fire and thereat may be easily and quickly operated for effectively smothering the flames before they can spread.

A further object is the provision of a novel mobile fire-fighting unit having a wheeled carriage so constructed and arranged that the entire unit may be quickly moved to a desired position with respect to the fire and thereat instantly made available for directing and discharging a full charge of carbon dioxide upon the flames.

The present invention further comprehends a most convenient, positive and effective fire extinguisher that may be employed in instantly discharging a smothering, heavy blanket of carbon dioxide providing a most effective defense against relatively severe, large area fires.

A further object of the present invention is the provision of a novel palm-actuated trigger release and valve assembly for a fire extinguisher.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment it is to be understood that the same is susceptible of modification and change and comprehends other details, arrangement of parts, features and constructions without departing from the spirit of the invention.

In the drawings:

Figure 1 is a view in front elevation of the novel mobile or portable fire extinguisher.

Fig. 2 is an enlarged fragmentary view of the upper end of the extinguisher and showing more clearly the palm-actuated trigger and the manner of operation.

Fig. 3 is a view of the parts shown in Fig. 2 but with the hood and palm trigger broken away or in cross-section to more clearly show the valve actuating mechanism.

Fig. 4 is a fragmentary view of the upper end of Fig. 3 but showing the palm-actuated trigger 55

2

depressed to discharge and deliver the carbon dioxide gas and snow.

Fig. 5 is a view in vertical cross-section taken on the irregular line 5—5 of Fig. 3.

Fig. 6 is a view in vertical cross-section of the valve construction taken in a plane represented by the line 6—6 of Fig. 5.

Referring more particularly to the embodiment shown in the drawings and selected to illustrate the novel invention, the present mobile or portable fire extinguisher comprises a tank or cylinder 1 containing carbon dioxide or the like and provided with a valve assembly 2 detachably connected to the upper end of the tank or cylinder and adapted to be actuated by depressing a trigger rod 3 which opens the valve and permits discharge of the carbon dioxide under pressure through an outlet nipple 4, connecting hose 5 and horn assembly 6. The trigger rod 3 is preferably provided with an enlargement or rounded screw head 7 biased or spring-pressed into normally raised position by means of an encompassing coil spring 8 seating against the under surface of a palm-actuated trigger 9 and the upper surface of a tubular support 10 for a carriage 11.

The trigger 9 is pivotally mounted at 12 upon the tubular support 10 which in the disclosed embodiment is shown as substantially inverted U-shaped having downwardly projecting legs 13, 13 adapted to engage the floor or other support when the device is not being transported, and the upper connecting part 14 providing a handle by which the extinguishing unit may be transported to a place of storage or for fighting a fire. The tank or cylinder 1 is supported or carried by the mobile carriage 11 by means of a pair of spaced straps or bands encompassing the tank or cylinder 1, the upper one 15 being shown in Fig. 1 secured to the legs 13 while the lower one (not shown) carries the wheeled support 16 having an axle 17 and a pair of wheels 18 for quickly transporting the fire extinguisher, when necessary and to wherever desired.

The trigger rod 3 at its lower end engages a discharge pin 19 guided in its longitudinal path by means of an annular collar 20 formed or provided in a valve insert 21 threaded into the upper end of the valve body 22, and sealed by means of a packing 23. The lower end of the discharge pin seats against the head 24 of a screw or the like retaining a resilient or rubber-like sealing ring or gasket 25 carried in or upon the upper end of a plunger 26. The reduced end 27 of the plunger is carried by the upper end of a coil

spring 28 with that end of the spring seating against the plunger and the lower end seating against the end of a threaded nut 29 threaded into the lower end of the valve body and in turn receiving the upper end of a length of siphon pipe or tubing 30 depending into the tank or cylinder 1. The lower end of the valve body is threaded at 31 for attachment to the tank or cylinder and is sealed thereto.

The sealing ring or gasket 25 has sealing engagement with the valve seat 32 provided at the reduced lower end of the valve insert 21 to thereby seal and prevent the flow from the cylinder 1 to the space encompassing the discharge pin 19 and leading to the discharge passage 33 in the valve outlet nipple 4 connected to the hose 5 and horn 6. A soft copper washer or other packing 34 may be provided between the end of the valve insert 21 and the shoulder 35 formed in the valve body. A safety plug 36 is provided for normally closing a port 37 leading to the inlet in the valve body.

Mounted upon the upper end of the tank or cylinder is a conical carriage hood 38 provided with an elongated opening 39 for ready access to certain desired or required data appearing on the dome of the tank and a smaller opening 40 through which projects the outlet nipple 4 carrying at its outer end a diffusion tip 41.

To prevent the trigger or handle 9 from being accidentally or unintentionally depressed and thereby discharging a stream of carbon dioxide, provision is made for locking this trigger against movement until such time as the necessity arises. This comprises a safety lock pin 42 and a seal wire projecting through an opening in a side wall or flange 43 on the trigger and into the upper end 14 of the tubular support 10 on the carriage 11.

The present novel mobile unit may be quickly rolled into position for fighting a fire and all that is required to make it available for use is to remove the locking pin 42, disengage the horn 6 from its resilient clip 44 provided on the band or strap 15 and direct or aim it with one hand toward or upon the fire. Then by depressing the trigger or handle-actuated part 9 with the other hand, an accurate full charge of carbon dioxide is directed upon the flames. By reason of this novel construction, the operator can at all times remain a safe distance from the fire and he is assured of instant discharge of a smothering and heavy blanket of carbon dioxide.

Having thus disclosed my invention, I claim:

1. A mobile fire extinguisher adapted to be rolled speedily into position for fighting a fire, comprising a wheeled carriage having a support providing a handle at its upper end for transporting the carriage, a container for carbon dioxide and the like mounted on the support, a valve assembly mounted upon the upper end of the container and provided with a spring-biased actuating rod projecting thereabove with its upper actuating end disposed above the handle, and a palm-actuated trigger pivotally mounted on the handle and engaging the actuating end of the rod whereby when the trigger is depressed the valve is opened and permits discharge of the carbon dioxide.

2. A mobile fire extinguisher adapted to be quickly moved into a position for extinguishing

a fire, comprising a wheeled carriage provided with an inverted U-shaped support providing a handle at its upper end for moving the carriage, a container mounted upon the support beneath the handle, a valve unit mounted upon the container and provided with an upstanding valve actuating member projecting through and guided by the handle for opening the valve when depressed, a spring-actuated closure for normally holding the valve in closed position, and a hand-operated trigger pivotally mounted on the handle at the upper end of the support and engaging the valve actuating member for most accessible operation and when the handle is pressed depresses the actuating member for opening the valve and discharging the contents of the container.

3. A mobile fire extinguisher adapted to be rolled speedily into position for fighting a fire, comprising a wheeled carriage having a substantially inverted U-shaped support with the connecting portion providing a handle at its upper end for transporting the carriage, a container mounted on the support and adapted to contain a fire extinguishing fluid, a valve assembly mounted upon the upper end of the container and provided with a trigger rod projecting thereabove and through and guided by the handle, and a hand-operated trigger pivotally mounted on the handle at the upper end of the support and engaging the trigger rod whereby when the trigger is depressed the valve is opened and permits discharge of the contents of the container.

4. A mobile fire extinguisher adapted to be quickly moved into a position for extinguishing a fire, comprising a wheeled carriage provided with an inverted U-shaped support with the ends providing supporting legs and the upper connecting portion providing a handle for transporting the extinguisher, a container carried by the support, a valve unit for the container and provided with an upstanding actuating rod for opening the valve when depressed, said rod having its upper end supported and guided by the handle, a spring-actuated closure for normally holding the valve in closed position, a hand-operated trigger pivotally mounted on the handle above the upper end of the actuating rod and when pressed downwardly depresses the actuating member for opening the valve and discharging the contents of the container, and a conical-shaped hood providing a protective enclosure for the valve unit actuating rod and associated parts.
